UNITED STATES PATENT OFFICE

JOSEPH E. BEHSE, OF SAGINAW, MICHIGAN, ASSIGNOR OF ONE-FOURTH TO GEORGE C. WILLCOX, OF SAGINAW, MICHIGAN

ROLLER TAIL-SKID FOR AIRPLANES

Application filed January 23, 1931. Serial No. 510,611.

This invention relates to wheels or rollers for the tails of airplanes, and has for its object the provision of an improved roller which will roll freely in a forward or back direction, which will tend to guide the plane in a straight line when it is moving forward or backward, yet will slide sideways with comparative ease when the plane is being turned, and which will resist wear when in constant service on the hard-surfaced runways of modern flying fields.

Essentially, it comprises a roller having its axle suitably secured to and extending transversely of the tail of the ship, either rigidly or at the end of a spring strut. Its tread is wide and curved in an arc so that it can slide sideways easily over the ground without a tendency to dig in. The tread is made with a smooth surface from hard, wear-resisting material which offers a minimum of resistance to sideways sliding motion.

With the increasing number of planes using flying fields, the old style tail-skid having a drag or shoe is no longer suitable for use on modern fields. Used on turf fields by a large number of planes they destroy the surface faster than new growth of grass can repair the damage. As a result they are being ruled off of the turf fields.

Also, runways of stone, cinder, or concrete are now used on most large busy fields. This type of surface very rapidly wears out the dragging shoe of the prior style of skid.

Since wheel-brakes have come into general use on planes, the braking effect of a dragging skid is no longer necessary for bringing a landing ship quickly to rest.

As a result of the above mentioned conditions, wheels have been substituted for skids on many planes. These wheels, however, have generally been smaller adaptations of the main landing wheels of the plane, fitted with rubber tires. Since these tires resist sideways sliding motion it has been necessary to swivel or caster the wheels to make the plane maneuverable.

A tail-wheel mounted so that it is free to swivel has several disadvantages. When handling the plane in the hangar it can not be readily backed, because the tail-wheel is

apt to turn the tail in any direction. This necessitates the attention of a man at the tail to see that the wheel is kept pointed in the proper direction.

A second disadvantage is that in handling the plane in a cross-wind, the swiveled wheel does not resist the frequency of the tail to be blown sideways. Consequently planes so equipped are especially apt to "ground-loop."

I have found that my improved roller tail skid is free from these objections to both the sliding tail skid and the castered tail wheel.

Referring to the drawing: Fig. 1 is a side view of a tail-roller according to my invention.

Fig. 2 is an elevation of the roller shown in Fig. 1, taken in a plane parallel to the axle.

Fig. 3 is an elevation similar to Fig. 2, showing a differently shaped roller, also made according to my invention.

The roller 1 is preferably made of aluminum or other light metal with a ring of steel 2 cast into its periphery to form the tread wearing-surface. It is preferably fitted with an oil-less bearing 3, and is journalled upon a tubular steel axle 4 secured in a fork 5. Spring washers 6 bear against the ends of the bearing 3 and seal the bearing surfaces from dirt, and also prevent excessive wear on fork 5 due to end thrust.

Fork 5 is suitably secured beneath the tail of the airplane, either rigidly or at the end of a spring strut 7, as shown in Fig. 1. In either case, the axle fork 5 is normally fixed relative to its upright axis, so that it can not caster or swivel under ordinary conditions.

The diameter of the roller and the width of its tread are determined by the weight it is to carry, which of course varies with different sizes of ships. In every case it is calculated on the same basis as the diameter and size of the tires on the main landing wheels. It is desirable to maintain a ratio between the diameter of the roller and the width of its tread which will produce a compact unit causing a minimum of wind resistance when the plane is in flight.

The shape of the tread, viewed in cross-section, may be flat, elliptical or arcuate. Figs. 1 and 2 show a roller with a flat tread; Fig. 3 is a spherical roller. It is essential, however, that the edges of the tread shall be rounded, so that the roller can slide sideways without cutting into the ground.

This novel roller combines the good points of the old tail-skid and the rubber-tired swiveled wheel. It slides sideways as easily as the tail-skid it replaces, and it rolls as freely in a forward direction as does the swiveled wheel. In addition it provides the guiding effect of the old skid, when a ship is landing or taxiing along the ground, since it will naturally travel more freely when it rolls forward than when it slides sideways. A puff of wind across the ship can not readily blow the tail around, as it can in the case of a ship having a freely swiveled tail wheel. This is a special advantage on icy surfaces. Also a tail-skid assembly using my wheel is much lighter than the assembly of a swiveled wheel.

The character of the tread distinguishes this improved roller from any previous tail wheels. It is hard and smooth to resist wear and to slide easily over turf, dirt, or cement surfaces which are gripped by rubber and which compel the swivel-mounting of any conventional wheel.

It will wear much longer than the sliding skid if used on hard runways, and it costs much less to build than the wire-spoked wheels with pneumatic tires which have been fitted to large ships heretofore.

I have shown and described a roller fixed permanently transversely of the plane. I do not wish to limit myself to this construction, however. Within the scope of the appended claims is included, for example, a structure including a swiveled mounting for the fork 5, provided with means for locking the roller in a fore and aft direction during normal service, but which can be unlocked, if desired, so that the roller can caster freely, to permit easier handling of the ship, as when moving it about in the hangar.

Having thus described my invention, what I claim and desire to secure by Letters Patent is:

1. In an airplane, in combination, a supporting member mounted in a downwardly depending position beneath the tail of said airplane, a bearing fork fixed to the lower end of said member, a roller journaled in said fork, said supporting member and said fork so mounted as to normally maintain the rotative axis of said roller perpendicular to the vertical plane of the longitudinal axis of said tail, said roller provided with a hard non-resilient smooth-surfaced tread and rounded at its edges.

2. In an airplane, a roller journaled beneath the tail thereof to support the tail when

the airplane is on the ground, said roller having its axis normally fixed against casting movement so that it rotates only in the longitudinal vertical plane of the tail, and having a hard smooth non-resilient tread rounded at its edges, whereby it is adapted for sideways sliding motion on the ground.

In testimony whereof, I affix my signature.

JOSEPH E. BEHSE.
